UNITED STATES PATENT OFFICE

JOHANNES STICH, OF BERLIN-SIEMENSSTADT, GERMANY, ASSIGNOR TO SIEMENS & HALSKE AKTIENGESELLSCHAFT, OF SIEMENSSTADT NEAR BERLIN, GERMANY

REPEATER

Application filed December 7, 1931, Serial No. 579,357, and in Germany March 2, 1931.

The present invention relates to a circuit arrangement for transmission of impulses in telephone systems with automatic operation. In arrangements of this type it is known that the loop normally extends over the windings of a choke coil or the like on the outgoing side of the impulse repeater and that this choke coil is short-circuited during pulsing to improve the impulse transmission. 10 This frequently gives rise to the occurrences that the impulse receiving relay, upon the completion of an impulse series, is influenced by induced impulses caused by the whole choke coil being connected up, thus bringing about faulty connections. The object of the present invention is to eliminate this drawback in a simple manner, this according to the invention being accomplished by the control devices which are required to set up the 15 connection and which are influenced while an impulse series is being transmitted, being caused, after the impulse series has completed its operation, to connect up the windings of the choke coil stage by stage so as to bridge 20 the outgoing leads.

An embodiment of the present invention is shown in the drawing. When the junction line VL is seized in some manner or other the bridging relay S, as usual, will be energized, causing relay V1 to respond over earth, battery, relay V1, contact 1s, by opening contact 8s and closing contact 1s. Relay V1 closes contact 2v1 so that the following circuit is set up: earth, 30 contact 2v1, relay V2, relay V1, battery, earth. Due to the short-circuit at contact 1s, relay V1 only is able to actuate its contacts. If the subscriber who has seized the junction line VL now sends out impulses, relay S will 35 be deenergized in accordance with the interruptions of the impulse series. The impulses received by relay S are transmitted at contact 7s to relay A in known manner.

When relay S releases at the first interruption of the impulse series, the contact 1s will be opened and contact 8s closed. This removes the short-circuit for relay V2 with the result that it is energized. Relay V1, by reason of its slow action, is not deenergized 45 due to the short-circuit of relay V1 at con-

tact 8s since this contact is reopened before relay V1 is due to release, a fresh circuit being set up for relay V1 over contact 1s. Relay V2 is not influenced even by its short circuit at contact 1s or by the further interruptions of the impulse series as it too operates as a slow-acting relay. The two relays V2 and V1, therefore, remain energized during the impulse series. 55

Contacts 4v2 and 5v2 of relay V2 are adjusted so that on the operation of the relay contact 4v2 is closed shortly after the armature starts its stroke whereas contact 5v2 is not closed until the armature has nearly completed its stroke. Similarly, upon the release 60 of the relay, contact 5v2 is opened shortly after the armature of the relay starts its return to normal while contact 4v2 is not closed until the armature has nearly reached its normal position. 65

The outgoing side of the junction line is disconnected from the condensers by relay V2 opening contacts 3v2 and 6v2, and winding I of the choke is short-circuited by the closing of contact 4v2, accomplished before contact 5v2 is closed. Said contact 5v2 is closed shortly thereafter with the result that windings I and II of choke Dr are short-circuited and a loop is formed over the speaking leads, insuring an impulse transmission 70 satisfactory in every respect. 75

When relay S remains permanently energized at the end of the impulse series, contact 1s also remains permanently closed, and consequently keeps relay V2 short-circuited. Relay V2, therefore, releases at the end of the impulse series whereas relay V1 still remains energized over earth, battery, relay V1, contact 1s and earth, even after the impulse 80 series has ended. When relay V2 is deenergized, contacts 4v2 and 5v2 will be opened in reverse order. Thereby, winding II only is connected up by the opening of contact 5v2 85 as soon as relay V2 starts to release. The short-circuit for winding I is not removed until contact 4v2 is opened when the armature has nearly reached its normal position. The opening of contact 4v2 reconnects winding I 90 of the choke coil across the outgoing line. 95 100

The induced impulses are suppressed to a minimum by this reconnecting up of the choke Dr stage by stage and in this manner are prevented from exercising an influence 5 on the impulse receiving relay.

What is claimed is:

1. In an impulse repeater, an incoming and an outgoing line, an impedance comprising a plurality of sections normally bridged across 10 said outgoing line, means responsive to impulses received over said incoming line for repeating like impulses over said outgoing line, and means for short-circuiting said impedance during each impulse train and for 15 successively reconnecting the sections of said impedance across said outgoing line, one after the other, at the termination of the impulse train.

2. In an impulse repeater, an incoming 20 and an outgoing line, an impedance comprising a plurality of sections normally bridged across said outgoing line, means responsive to impulses received over said incoming line for repeating like impulses over said outgoing line, and means for successively short-circuiting 25 the sections of said impedance, one after the other, at the beginning of an impulse train and for reconnecting said impedance across said outgoing line at the termination 30 of the impulse train.

3. In an impulse repeater, an incoming and an outgoing line, a repeating relay bridged across said incoming line, an impedance bridged across said outgoing line, said 35 impedance being divided into a plurality of sections, a slow acting relay operated during each impulse series to short-circuit said impedance, and means controlled by said relay when it releases at the end of an impulse 40 series for successively reconnecting the sections of said impedance across said outgoing line, one after the other.

4. In an impulse repeater, an incoming and an outgoing line coupled by condensers, a 45 direct current bridge across said outgoing line comprising a plurality of impedances, means responsive to impulses received over said incoming line for repeating said impulses over said outgoing line, and means effective 50 during each impulse series for disconnecting said outgoing line from said con-

densers and for short-circuiting said impedance bridge, said means being also effective at the end of each impulse series to successively reconnect said impedances across said outgoing line, one after the other. 70

5. In an impulse repeater, an incoming and an outgoing line, a plurality of impedances normally bridges across said outgoing line, means responsive to impulses received over said incoming line for repeating said impulses over said outgoing line, a slow acting relay operated at the beginning of each impulse series to short-circuit said impedances for the duration of the series, and contacts on said relay for successively connecting said impedances across the outgoing line, one after the other, when said relay releases at the termination of the impulse series. 75

6. In an impulse repeater, an incoming 80 line and an outgoing line coupled by condensers, a plurality of impedances bridged across said outgoing line, a repeating relay bridged across said incoming line and responsive to impulses to repeat the same over 85 said outgoing line, a slow acting relay operated at the beginning of each impulse series and remaining operated throughout the series, and contacts on said slow acting relay for disconnecting said outgoing line from 90 said condensers and short-circuiting said impedances when the relay is operated, and for reconnecting said outgoing line to said condensers and successively reconnecting said impedances across said outgoing line, one at 95 a time, when the relay releases at the termination of the impulse series. 100

7. In an impulse repeater, an incoming line and an outgoing line, means responsive to impulses received over said incoming line 105 for repeating like impulses over said outgoing line, a relay operated throughout each impulse series, and means controlled by said relay at the end of each impulse series for bridging impedances across said outgoing 110 line and for subsequently increasing such impedance.

In witness whereof, I hereunto subscribe my name this 23rd day of October, A. D. 1931.

JOHANNES STICH.
